FIG. 7

INVENTOR

JOSEPH ABRAMOWITZ,

By *Rufus Knecht* ATTORNEY.

Patented Jan. 13, 1925.

UNITED STATES PATENT OFFICE.

JOSEPH ABRAMOWITZ, OF MADISON, ILLINOIS, ASSIGNOR OF ONE-HALF TO JOHN J. SELB, OF VENICE, ILLINOIS.

ATTACHING DEVICE FOR RUBBER SHOE HEELS.

Application filed September 27, 1922. Serial No. 590,834.

To all whom it may concern:

Be it known that I, JOSEPH ABRAMOWITZ, a citizen of the United States, residing at Madison, county of Madison, and State of Illinois, have invented a certain new and useful Improvement in Attaching Devices for Rubber Shoe Heels, of which the following is a specification, reference being had to the accompanying drawing, forming a part thereof.

This invention relates generally to boots and shoes and, more particularly, to a certain new and useful improvement in attaching devices for rubber-heels or lifts to boots, shoes, and the like, the chief object of my present invention being to provide a simple, readily produced, and inexpensive device, whereby rubber-heels or lifts may with facility and convenience be detachably fastened upon the shoe.

With the above and other objects in view, my present invention resides in the novel features of form, construction, arrangement and combination of parts hereinafter described and afterwards pointed out in the claims.

In the accompanying drawing.

Figure 1 is a plan view of the blank from which the attaching-device proper is stamped and formed;

Figure 2 is an edge view of such blank;

Figure 3 is a plan view of the finished or completed attaching-device proper;

Figure 4 is an edge view of the device;

Figure 5 is a plan view of a rubber-heel or lift with which the attaching-device proper is adapted for co-operation;

Figures 6 and 7 are longitudinal and transverse sectional views of the heel or lift taken approximately on the lines 6-6 and 7-7, respectively, of Figure 5; and

Figure 8 is a longitudinal sectional view of the attaching device and heel or lift of Figures 3 and 5 in attached position upon a shoe, the latter being fragmentally shown.

Referring now in detail and by reference characters to the accompanying drawing, which illustrates a preferred embodiment of my invention, my present shoe-heel attaching device is in the form substantially of a plate A by suitable blanking, punching, and forming dies constructed from the flat section 1 of suitable preferably metallic material shown in Figure 1 to comprise in-

tegrally a pair of more or less elongated 55 ribs, keys, tenons or the like 2-2 disposed in the same plane in the form of a cross, as best seen in Figure 3, and being substantially of dove-tail form, having preferably beveled or under-cut side walls 3, as shown 60 in Figure 4. Projecting laterally from each wall of each rib 2 at the base thereof, as shown in Figure 3, are spaced flat webs or flanges 4 formed with nail or tack-apertures 5, the plate A having a central threaded 65 opening 6 and each rib 2 being suitably provided preferably at or adjacent its opposite ends with tapped threaded openings or apertures 7, for purposes shortly appearing.

Adapted for co-operation with the plate 70 A, is a rubber heel or lift B suitably formed upon its upper face with crossed grooves or recesses 8-8 of dimensions and with beveled side walls 9 to snugly accommodate the ribs or keys of plate A. On its under face, heel 75 or lift B is formed with preferably a plurality of nail or screw-head cavities 10 having communication respectively with the grooves 8 by means of transverse nail or screw apertures 11. 80

In use, the plate A is fitted flatwise at its webs 4 upon the exposed face of the lower fixed heel lift or shoe-sole 12, its ribs or keys 2 being presented outwardly, and rigidly and substantially permanently fastened to 85 the shoe as by means of tacks or the like 13 projected through the openings or apertures 5 of webs or flanges 4 into the shoe-sole 12. A shoe-heel or lift B is now disposed with its grooves 8 presented towards ribs 2 and 90 heel or lift B then by suitable manipulation sprung or forced into snug key-engagement at its grooves 8 with the plate A at its ribs 2. By means then of preferably a plurality of headed screws or the like 14 projected through heel or lift apertures 11 and threaded into engagement with plate A at its openings 6 and 7, the heel or lift B is detachably secured to the plate A and thus, in turn, effectively fastened detachably to the shoe. 95

My new shoe-heel attaching means is simple and inexpensive in form and construction, and enables the ready, convenient, and quick attachment and replacement of rubber heels, lifts, and the like upon boots 100 and shoes, without in the slightest degree interfering with or reducing the full effectiveness of the rubber-heel or lift upon the

shoe and without the direct employment of nails or other such fastening means.

I am aware that minor changes in the form, construction, arrangement, and combination of the several parts of my new shoe-heel attaching means may be made and substituted for those herein shown and described without departing from the nature and principle of my invention.

10 Having thus described my invention, what I claim and desire to secure by Letters Patent is:

1. As a new article of manufacture, an attaching-device including a pair of keys of dovetail formation in section, said keys intersecting one with the other on the same plane and being adapted for extended engagement throughout their length with the heel or lift, and webs projecting laterally from said keys at the base thereof, the device being adapted to fit at said webs flatwise upon and under the shoe at the heel thereof and said webs being provided with apertures for accommodating members for fastening the device to the shoe.

2. As a new article of manufacture, a sheet metal plate formed to include a pair of offset keys disposed in the same plane in intersecting cross relation and each being of hollow dovetail formation in section, and spaced webs projecting laterally from each wall of each key at the base thereof, the plate being adapted to fit at said webs only approximately flatwise upon and under the shoe at the heel thereof and said webs being provided with apertures for accommo-

dating members for fastening the plate to the shoe.

3. In combination, a shoe, a heel having a pair of intersecting beveled grooves upon its upper face, a heel attaching device including a pair of intersecting keys of dovetail formation in section and each having a threaded opening, and webs projecting laterally from said keys at the base thereof and disposed flatwise under the shoe, members having engagement with the webs and shoe for fastening the device to and upon the shoe, the plate and heel being adapted for groove and key interengagement, and screws projecting through the heel and into said key-openings for detachably securing the heel to the shoe.

4. In combination, a shoe, a rubber heel having a pair of intersecting beveled grooves upon its upper face, a heel attaching device including a pair of intersecting keys of dovetail formation in section and each having a threaded opening, and webs projecting laterally from said keys at the base thereof and disposed flatwise under the shoe, members having engagement with the webs and shoe for fastening the device to and upon the shoe, the heel being adapted for sprung engagement at its grooves with said keys, and screws projecting through the heel and into said key openings for detachably securing the heel to the shoe.

In testimony whereof, I have signed my name to this specification.

JOSEPH ABRAMOWITZ.
